REACTION PROPULSION SYSTEM

Aldo V. La Rocca, Cincinnati, Ohio, assignor to General Electric Company, a corporation of New York
 Filed Sept. 28, 1960, Ser. No. 58,928
 1 Claim. (Cl. 60—35.6)

The present invention relates to a reaction propulsion system and, more particularly to a compounded reaction propulsion system which makes use of three processes of heat addition to a working fluid.

These processes can be used separately or in combination to obtain a range of thrust and specific impulses when a working fluid is expanded through a nozzle for the creation of thrust. In such a manner a device better capable of matching the propulsive requirements for several applications is obtained, resulting in an improved overall performance.

In any reaction propulsion system, it is desirable to have high equivalent specific impulse. This is expressed as:

$$\bar{I} = \frac{Ft_f}{W_{ps}}$$

The equivalent specific impulse ($\bar{I}$) can thus be defined as the product of the thrust (F) times the propulsion time (t_f) which product is the total impulse, all divided by the weight of the propulsion system (W_{ps}). In the more general case where the thrust is not constant the equivalent specific impulse is expressed by the integral of the thrust over the propulsion time divided by the propulsion system weight and expressed as:

$$\bar{I} = \frac{\int_0^{t_f} F dt}{W_{ps}}$$

To maximize the equivalent specific impulse i.e. to optimize the propulsive system for a given application, particular values of the specific impulse are required. Specific impulse is defined as the exhaust jet velocity (V_{ex}) divided by the standard acceleration of gravity (g_0) thus:

$$I_{sp} = \frac{V_{ex}}{g_0}$$

These values of the specific impulse can be greater than those possible with chemical systems i.e. those systems making use only of the energy stored in the chemical bonds of the propellants or generated in an exothermic reaction such as oxidation or combustion.

Other means of achieving high specific impulses for systems discharging to a vacuum can be obtained by raising the settling chamber temperature to levels above those possible by a chemical reaction process. Another possible means is that of adding energy in a form other than thermal to the working fluid. Of the first class of devices the electrical arc reaction engine makes use of addition of thermal energy at a very high temperature to a working fluid. The range of settling chamber temperature depends on the dilution of the arc by the amount of the working fluid injected at a given level of electrical power. The usable stagnation temperatures are limited basically by two phenomena, (1) the containment problem or the structural and mechanical integrity of the chamber and of the electrodes which have to withstand very large heat fluxes. And (2) the occurrence of chemical processes such as dissociation and physical processes such as changes of state and ionization. Both of these would impair the efficiency of the device, if the associated energies could not be recovered and converted to thrust in the exhaust nozzle.

Examples of the second class of devices are the plasma

2

accelerator and the ion accelerator. They increase the kinetic energy of the jet by electromagnetic or electrostatic forces. These, on the other hand, face several development problems. Furthermore their intrinsic characteristics seem to indicate advantageous performance only for propulsive requirements resulting in optimizing specific impulses several times larger than those of chemical systems. The gap that is left in the specific impulse between the chemical and the second class of devices just described offers a specific impulse range which is required to optimize propulsive systems for several applications of earth orbiting vehicles. It is this gap in which the propulsion system of the present invention is designed to operate.

The main object of the present invention is to provide a reaction propulsion system that will deliver a wide range of thrust variation with highest equivalent specific impulse and with a minimum of variable geometry and control complexity.

A further object is to provide such a system which does not have the storage, temperature and cooling problems of the normal high specific electrothermal engines.

Another object is to provide such a system wherein thrust augmentation is obtainable without any variable geometry.

Briefly stated, the invention provides a reaction propulsion system with a heating chamber, electrical energy means in the heating chamber for heating the fuel, a source of exothermally decomposable fuel of the type which, when it decomposes produces products of a molecular weight of less than 16, and a converging-diverging nozzle downstream of the heating chamber to discharge the heated products of decomposition to produce thrust. A further modification provides a thrust augmenting means by which an additional reactant such as an oxidizing agent is introduced into a combustion chamber to raise the temperature of the decomposed products and provide higher thrust by discharging through a second converging-diverging nozzle downstream of the first nozzle.

While the specification concludes with a claim particularly pointing out and distinctly claiming the subject matter which I regard as my invention, it is believed the invention will be better understood from the following description taken in connection with the accompanying drawing in which:

The drawing is a schematic sketch of a reaction propulsion system of the present invention.

Referring to the drawing, the system consists of a heating chamber 10. Suitable storage means 11 supplies an exothermally decomposable compound to the chamber 10 through line 12 under control of valve 13. For illustrative purposes such a compound may be diborane, pentaborane, hydrazine, lithium hydrate or nitro-methane.

These compounds have the advantage of easy, stable and compact storage in the liquid form. Thus, the problems associated with the extremely low temperature (cryogenic) storage of some other proposed working fluid such as hydrogen and helium are avoided. Furthermore, the exothermic reaction of decomposition does away with the need for supplying the heat of vaporization which is required by other possible working fluids such as water. Such a reaction gives the added advantage that heat is released in the decomposition in an amount that can be up to 15% of the total heat that must be added to the working fluid.

The decomposition process may be spontaneous at the conditions existing in the heating chamber 10 or can be assured by appropriate decomposer devices 14 between the storage means 11 and the throat of the nozzle which may be a glow plug, a catalytic surface or the equivalent.

In the instant invention it is important that the fuel source 11 contain fuel which is exothermally decompos-

able and which is decomposable into products having a molecular weight of not more than fifteen.

These products represent a good working fluid for the propulsive device either by direct expansion to vacuum or with two further heat addition processes.

One of these processes provides heat to the decomposed fuel in chamber 10 by a suitable electrical energy discharge means 15 which is provided preferably, although not necessarily, centrally of chamber 10. This electrical energy discharge means may be conveniently an electric arc plasma generator, which is nothing more than a direct or alternating electrical current discharge of high intensity that heats the propellant, which is directed by suitable means at the end of line 12 to surround the arc, and adds energy to it. The term electrical energy discharge means is intended to include any such electric arc of this general type whether or not associated with electrical preheating schemes such as the more conventional electrical heaters of the resistance or inductance type. The electric arc may be suitably powered by the usual external means indicated generally at 16 for heating the decomposed products to a temperature far above those obtainable by chemical reaction.

The products of decomposition are heated in this manner to appropriately high temperatures compatible with the above mentioned containment and efficiency criteria. The heated products are then expanded (and thereby accelerated) through a first converging-diverging nozzle 17 into a combustion chamber 18 which surrounds the first chamber preferably concentrically. The exhaust 30 of this first nozzle is further or continuously expanded to the external ambient (vacuum) by means of a second converging-diverging nozzle 19 which can be considered as an extension of the first as far as the expansion process is concerned, although structurally it is attached to 35 the combustion chamber.

The propulsion system thus far described, by using an exothermally decomposable fuel that decomposes into products of decomposition having a molecular weight of not more than fifteen, permits an engine of a high specific 40 impulse without the disadvantages of the high temperature, high weight features and permits easy storability since the monopropellant is dense and easily storable under ordinary conditions.

A second feature of the instant invention is to provide augmented thrust to the propulsion system just described. This is carried out by another heat addition process in which an appropriate reactant such as an oxidizer in container 20 is fed to chamber 18, by means of a line 21 and control valve 22. The oxidizer is directed to regeneratively cool the internally placed chamber 10 and nozzle 17 and, by mixing it with the products of decomposition, which may or may not have been further heated by the electrothermal device 15 in chamber 10, further heat is added to the working fluid and 55 the thrust is augmented.

For the augmentation process the first nozzle 17 will behave as a torch or flame holder insuring sure starting, better mixing, and more efficient combustion. It can be seen that, in this configuration, the second nozzle 19 is 60 an extension of the first and preferably concentrically to provide a tandem arrangement. The advantages of this arrangement are several:

(1) The first 17 and second nozzles 19 essentially represent a single nozzle of very good area ratio for the 65 products of the first two heat addition processes which are decomposition and electrothermal heat addition. Furthermore, an aerodynamic or self-adjusting effect automatically ensures the proper attachment of the exhaust jet of the first nozzle 17 to the inner surface of the nozzle 19 at 23 for the best fluidynamic efficiency during operation of the two heat addition processes, namely, decomposition and electrothermal heat addition.

(2) Small amounts of a reactant (such as an oxidizer)

or working fluid can be bled through line 21 or a bypass portion 24 of line 12 under control of valve 25 respectively to regeneratively cool the first chamber 10 and nozzle 17 when needed. With the configuration shown, the cooling fluid is then mixed, burned to increase the temperature in the second chamber and expanded at high efficiency taking advantage of the self-adjusting feature mentioned above.

(3) When the reactant or oxidizer flow is increased to give full augmentation, the appropriately sized and located throat 26 of the second nozzle 19 downstream of the exit of the first nozzle controls the flow.

Thus, the tandem nozzle configuration actually performs as a variable nozzle without requiring movable hardware, and will be self-adjusting for any mode of operation.

While I have hereinbefore described a preferred form of my invention, obviously many modifications and variations of the present invention are possible in the light of the above teachings. It is therefore to be understood that, within the scope of the appended claim, the invention may be practiced otherwise than as specifically described.

I claim:

A reaction propulsion system comprising, in combination:

a heating chamber;

electrical high temperature energy discharge means disposed in the said chamber;

a source of exothermally decomposable fuel of the type which upon decomposition produces products of a molecular weight less than 16;

means connecting the said chamber and exothermally decomposable fuel source and directing the fuel into said chamber for exothermal decomposition and for heating by said energy means, after decomposition, to temperatures far above those obtainable by chemical reaction;

a converging-diverging nozzle connected to said heating chamber downstream thereof to expand and accelerate the heated products of decomposition;

a combustion chamber surrounding the exit from the said nozzle;

a source of oxidizer;

means connecting the said source of oxidizer with the said combustion chamber to introduce oxidizer therein to oxidize the expanded accelerated decomposition products emerging from the said nozzle to further increase their energy and to increase total mass flow;

second nozzle means connected to the said combustion chamber to discharge, expand, and further accelerate the said decomposition products and oxidizer.
